[57] **CLAIM**

The ornamental design for a wall-mounted hair dryer, as shown and described.

DESCRIPTION

FIG. 1 is a front elevational view of a wall-mounted hair dryer showing my new design, the handset being detached from the body of the hair dryer; and

FIG. 2 is a right side elevational view of the wall-mounted hair dryer seen in FIG. 1, but with the handset attached to the body of the hair dryer;

FIG. 3 is a top plan view thereof;

FIG. 4 is a bottom plan view thereof;

FIG. 5 is a left side elevational view thereof.

FIG. 3

FIG. 4

FIG. 5
